KITE

Application filed June 7, 1928. Serial No. 283,538.

Our invention relates to kites, and more particularly to certain improvements in the construction of kites whereby they will fly more steadily and more nearly perpendicular and whereby they can be made ornamental by the addition of certain extensions or additions to the main body structure, and thus be produced in various forms or designs.

10 In order to fully explain our invention, we have shown certain embodiments thereof on the accompanying sheet of drawings, which we will now describe.

Figure 1 is a front elevation of a kite embodying our invention, certain possible extensions or additions being indicated in broken lines, and only part of the body being covered;

15 Figure 2 is a similar view showing the main body structure with another modification in the way of extension or addition thereto indicated in broken lines and partially covered;

20 Figure 3 is a perspective view of a kite embodying our invention, with additions and extensions thereto producing the form of an aeroplane;

25 Figure 4 is a sectional view taken on line 4-4 of Fig. 1, illustrating the form assumed by the body when the kite is in flight; and

30 Figure 5 is an end view of the body in flight showing how the opposite ends assume a form in flight which tends to maintain the kite in balance.

Referring now more in detail to the drawings, we will describe our improved kite construction and arrangement. The main body of the kite, no matter what form or 35 design is used, comprises an oval frame 6, of light bamboo or other light material, with a back bone member 7, across the frame 6, and extending below the same, as at 7^a. We have also shown it extended slightly above said frame, as at 7^b, for such uses as may be desired in ornamentation.

40 The oval frame is jointed at its opposite ends so that the end can flex or bend on a line crosswise through the frame for its longest 45 dimension. In the drawings, the frame 6

is shown cut, as at 6^a, 6^a, with the ends tied together with the Y-ends of a cross cord 8, which draws the opposite ends inwardly. This gives a rounded form to the end and at the same time permits each end to flex or 55 bend, as indicated at 9, Fig. 5, to form the slight angle 9^a longitudinally of each side of the body toward the middle. This operates to keep the kite balanced. The main body or oval portion of the kite also flexes or bends slightly along the back bone member 7, allowing the opposite ends of said body to bend backwardly in the manner indicated in the sectional view, Fig. 4. Thus the opposite sides of the body, that is, the 60 opposite ends of the oval body form, bend backwardly slightly when in flight, by reason of the air pressure, and the opposite ends bent on a line at right angles to said back bone. The flying cord 10 is attached 65 to the upper and lower sides of said oval body 6, at the back bone 7, as indicated in Figs. 1, 2 and 3. The oval body is covered with thin crepe or other suitable paper, P, only fragments of which are shown, as it is 70 understood that the paper covering is applied in the usual manner and can be of any 75 color or design for ornamentation.

Referring now to Fig. 1, we have shown in light broken lines, two additional frame 80 members or extensions, designated 11, 11, with a frame cord, designated 12, from the top of the oval frame 6, to the outer lower opposite sides and to the ends of said extensions 11, 11, and to the end of the back 85 bone member 7^a, as indicated in light broken line. This forms two extensions, as 13, of pointed form, covered with paper, as P'. The upper end of the back bone 7, at 7^b, is also provided with two short, light frame 90 members, 14, 14, tied together to form a pointed nose or bill at the upper end, as indicated in light broken lines. It will also be understood that this pointed portion is also covered with such color of paper as 95 may be desired to give the desired effect.

In Fig. 2, we have shown a curved member 15, indicated in light broken lines, secured to the lower end of the back bone member 7^a, with cords from its opposite 100

ends and extended to the position on said back bone member 7, crossed by the cross cord 8. This extension can be covered with the paper P, and decoration pieces 16, 5 can be secured to the cord, as indicated in broken lines.

In Fig. 3, we have shown the same main body and cross cord 8, holding the opposite ends of the oval member, and for the back bone have substituted the tapering body of 10 an aeroplane, designated 17, with propeller element, 18, and rudder elements 19 and 20, at the small end, substantially as indicated. The flying cord is attached at the two lower, 15 forward corners of the body 17, and in the middle at a point opposite the lower part of the oval frame member 6, substantially as indicated.

It will be seen in all of these various 20 modifications of the invention, the invention proper, that is, the main body frame 6, with a back bone element across the same in the middle thereof, is present and the extensions or additions are used to change the general 25 form or design of the kite and to give place for decorations, but the flying quality of all of the modifications is due to the main body construction which includes the elongated body frame 6, horizontally, with the 30 back bone member 7, vertically across the same, when the same is in upright position, and with a construction which permits said body to flex or bend backwardly at opposite sides along the line of the back bone, 35 as indicated in Fig. 4, and which also permits the opposite ends to flex or bend on a line coincident with the cross cord 8, which attaches to the jointed ends of said oval frame member 6.

40 We do not, therefore, limit our invention to the details shown for explanatory purposes except as we may be limited by the hereto appended claims forming a part of this application.

45 We claim:

1. In a kite, a body of oval form and having a back bone member across the middle thereof at right angles to the length of said oval form and extended beyond the 50 edge of said oval form, said body being made of flexible material whereby the opposite sides of said body can bend slightly backwardly along the line of the back bone, and a covering for said body.

55 2. In a kite, a body of oval form and having a back bone member across the middle thereof at right angles to the length of said oval form and extended beyond the 60 edge of said oval form, said body being made of flexible material whereby the opposite sides of said body can bend slightly backwardly along the line of the back bone, the outer opposite ends of said body frame 65 being adapted to bend slightly on a line

at right angles to the back bone member, and a covering for said body.

3. In a kite, a body comprising a light frame member of oval form horizontally, a back bone member across the middle portion thereof at right angles to the length thereof, the outer opposite ends of said oval form being jointed to permit flexing on a line lengthwise of said oval form, and a cross cord from one end of said frame 70 member to the other.

4. In a kite, a body of light flexible frame members, said body being substantially oval form from side to side, a back bone member from top to bottom of said frame and extended beyond the bottom thereof and in the middle of said body, and a cover for 80 said body frame, and two portions diagonally extended from the lower side of said oval body and at opposite sides of said back 85 bone member extension.

5. A kite including in combination, a body of oval form of light flexible frame structure, a back bone member in the form of an aeroplane body across the middle of said oval form at right angles to the length of said oval form and extended beyond the lower side of said oval frame member, whereby said oval body frame forms wings 90 on opposite sides of said back bone member, 95 said oval frame being cut and having its opposite ends tied together with a cord along the middle line and a flying cord attached to the underside of said body.

6. A kite including a body of light frame 100 construction in oval form with rounded ends and covered with paper and extending horizontally for its longest dimension, a back bone in the form of a box structure 105 in cross section and of tapering form longitudinally and secured across the underside of said body structure, the smaller tapering end of said back bone extending beyond the lower side of said body form and resembling an aeroplane, a covering for said body, and 110 flying cord from the underside of said structure, the opposite ends of said back bone having propeller and rudder elements, respectively, for the purpose indicated.

Signed at Los Angeles, Los Angeles 115 county, California, this 31st day of May, 1928.
